[57] CLAIM

The ornamental design for a building, as shown.

DESCRIPTION

FIG. 1 is a front elevated perspective view of the building, showing my new design.

FIG. 2 is an end view of the building, as seen from the left side of FIG. 1.

FIG. 3 is an end view of the building as seen from the right side of FIG. 1.

The rear of the building is plain and unornamented.

FIG. 1

FIG.3

FIG.2
